D. A. B. BAILEY, OF ST. JOHNSBURY, VERMONT.

Letters Patent No. 65,631, dated June 11, 1867.

IMPROVEMENT IN COMBINATION SQUARES.

The Schedule referred to in these Letters Patent and making part of the same.

TO ALL WHOM IT MAY CONCERN:

Be it known that I, D. A. B. BAILEY, of St. Johnsbury, in the county of Caledonia, and State of Vermont, have invented a new and useful Improvement in Combination Square; and I do hereby declare that the following is a full, clear, and exact description thereof, which will enable others skilled in the art to make and use the same, reference being had to the accompanying drawings forming part of this specification.

My invention consists in attaching to the ordinary steel square a triangular-shaped frame, made to slide upon the square, and to which is attached by a hinge at one end an adjustable face for the square in such a manner that it is made to rest upon the square at any desired angle; and also in the combination of parts, whereby they are made to serve many useful purposes, as will be hereinafter described.

Figure 1 represents a side view of the square and parts attached.

Figure 2 is a section through the line $x\ x$, fig. 1.

Figure 3 is a section through the line $y\ y$ of fig. 1.

Figure 4 is a view of the back side, with a portion of the sliding-frame cut away to show the square.

Similar letters of reference indicate like parts.

A represents the square. B is the sliding-frame, triangular in shape, with two of the sides of the triangle cut away on the top at a ; the lower portion is seen in dotted lines. In the shoulders of the part cut away there are slots, as seen at $b\ b$, through which the square passes. C is a set-screw, which holds the frame in any desired position on the square. The part B' of the triangle stands always at a right angle with the square. D is the face which is hinged to the frame or top of B' at d . E is a sliding-circle, attached to D. The centre of the circle is the joint d . f is a set-screw, attached to B' , whose head bears upon the circle and holds it in use, as seen at h' . These points form compasses. The set-screws hold them fast when they are used, and also when they are folded. The face-piece D has a long slot through which the square passes. This slot is seen in fig. 3 at J, with the square in the upper portion. This long slot is necessary to allow the face to be adjusted to any desired angle on the square. The various uses to which this combination is adapted will readily suggest themselves to mechanics.

Having thus described my invention, what I claim as new, and desire to secure by Letters Patent, is—

The frame B B', the face-pieces D, the circle E, and the points g g, the whole constructed, arranged, and held in position substantially as herein shown and described, in combination with the square for the purposes set forth.

D. A. B. BAILEY.
